UNITED STATES PATENT OFFICE.

GEORGE H. DIMOND AND WILBUR F. DIAL, OF BRIDGEPORT, CONNECTICUT,
ASSIGNORS TO THE WHEELER & WILSON MANUFACTURING COMPANY,
OF SAME PLACE.

TRIMMER MECHANISM FOR SEWING-MACHINES.

SPECIFICATION forming part of Letters Patent No. 540,907, dated June 11, 1895.

Application filed December 5, 1894. Serial No. 530,851. (No model.)

To all whom it may concern:

Be it known that we, GEORGE H. DIMOND and WILBUR F. DIAL, of Bridgeport, county of Fairfield, State of Connecticut, have invented an Improvement in Trimmer Mechanism for Sewing-Machines, of which the following description, in connection with the accompanying drawings, is a specification, like letters and figures on the drawings representing like parts.

This invention relates to mechanism for trimming the work adjacent to the seam in a sewing machine by means of a reciprocating or vibrating cutter, motion being imparted thereto by connections between it and some moving part of the machine.

In machines of the class described, so far as we are aware, it is very difficult, or altogether impossible, to throw the cutter into or out of operation without first slowing down or stopping the sewing machine, resulting in loss of time to the operator and necessitating the use of both hands to control the operation of the trimmer mechanism.

Our invention has for its object the production of a compact, simple and durable trimmer mechanism controllable at all times, whether the machine is running at high or low speed, and within easy each reach of the operator, who can guide the work with one hand and with the other quickly throw the cutter into or out of operation.

In accordance therewith our invention consists, in a sewing machine, of a cutter, a reciprocating cutter-carrier, a rocking lever connected thereto to reciprocate it, a rotating cam, connections intermediate said cam and lever, to rock the latter, and means to move said connections independently of the lever into and out of operative contact with the cam, to thereby actuate or stop the cutter-carrier during the operation of the machine, substantially as will be described.

Other features of our invention will be hereinafter described and particularly pointed out in the claims.

Figure 1, in end elevation and partly broken out, represents a sufficient portion of the outer end of the overhanging arm of a sewing-machine to be understood with our invention

applied thereto. Fig. 2 is a side elevation thereof, partly broken out. Fig. 3 is a vertical transverse section taken on the line $x-x$, Fig. 1. Fig. 4 is a top view of a portion of the mechanism shown in Fig. 2, and Fig. 5 represents the surface of the actuating-cam developed.

Referring to the drawings, the arm A, needle and presser-bars A' and A² respectively, and the needle-bar actuating-shaft A³, are and may be of usual construction and operation, the same forming no part of our invention.

The trimming blade or cutter a is secured in usual manner to a reciprocating cutter-carrier a' mounted in suitable bearings in the head A^x of the arm A, said cutter-carrier being slotted at its upper end to receive a slide-block a² connected by a species of ball and socket joint to one arm b of a rocking lever, shown in Fig. 3 as screwed upon the threaded and reduced end of a hollow sleeve b² mounted to rock in the bearing b³ in a stand B, secured to the overhanging arm, in suitable manner, as by screws s. The sleeve is shouldered internally at b⁴ and has an annular flange b⁵ at one end to rest against the bearing b³, the attached portion of the rocking lever resting against the other end of said bearing and thereby preventing longitudinal movement of the sleeve therein.

A shouldered shaft c provided with a suitable thumb-nut c' and threaded at its extremity, as at c², is passed through the sleeve b² and through an arm d held on and to be moved by the shaft by a suitable nut c^x. A spring s' within the sleeve surrounds the reduced portion of the shaft c between the shoulder b⁴ of the sleeve and the larger part of the shaft, so that the spring normally tends to keep the parts in the position shown in Fig. 3.

A stud d', secured to the arm d and projecting from its inner side, enters a suitable hole in the arm b' of the rocking lever, so that movement of the arm b about its pivotal support will also swing the rocking lever and its attached sleeve, as shown in full and dotted lines Fig. 2, or vice versa.

By moving the shaft c in the direction of 100

the arrow Fig. 3, the arm d will be moved into dotted line position, but without withdrawing the stud d' from engagement with the arm b' , said stud having a depression d^x in its inner end. See dotted lines Figs. 3 and 4.

A suitable pin or post d^2 on the swinging arm, extends from its inner face and has thereon a roll d^3 to enter the groove e of an actuating cam E , fast on the needle-bar actuating shaft A^3 . The shape of the groove e in the cam, shown developed in Fig. 5, is such that when the roll d^3 is in engagement therewith, rotation of the cam will swing the arm d , and by means of its connection with the lever b , b' , the cutter-carrier a' will be reciprocated. The rear wall of the cam groove e is of greater diameter than the front wall, as shown in Figs. 2 and 5, so that when the roll d^3 is in dotted line position, Fig. 3, it can be swung to the right, viewing Fig. 2, to clear the front wall of the groove e , and thereby move the cutter mechanism into inoperative position; but the higher rear wall will act as a barrier against movement of the roll d^3 to the left, and consequently prevents throwing down of the cutter into the path of the hook.

When it is desired to throw the cutter out of operation, the operator grasps the thumb-nut c' and pushes it in the direction of the arrow Fig. 3, thereby moving the swinging arm d bodily away from the side of the arm A and withdrawing the roll from the cam groove e . A partial turn of the thumb-nut in the direction of the arrow Fig. 2, then swings the arm d and carries the roll to one side of the cam. The stud d' is thereby brought into position to permit the pointed end of a screw 10 to enter the depression d^x , to positively hold or lock the mechanism out of operation, the adjacent portion of the arm A being cut away to permit the swinging movement of the stud d' . The rotative movement of the thumb-nut and shaft c also turns the lever b , b' , by means of the connecting stud d' into the dotted line position shown in Figs. 1 and 2, to lift the cutter carrier and maintain it in inoperative position, with the cutter lifted away from the work.

An adjustable stop pin c^4 , shown as a screw 50 extended through the thumb-nut c' , limits the movement of the shaft c in the direction of the arrow Fig. 3, so that it may not be pushed out to an unnecessary extent.

The spring s' keeps the roll d^3 in engagement with the cam when the cutter-carrier is reciprocated, or holds the stud up against the bottom of the cut away or recessed part of the overhanging arm when the cutter-carrier is inoperative.

The cutter may be thrown into and out of operation, during the operation of the machine, by a slight movement of one of the operator's hands, and the whole mechanism is mounted within convenient reach of the operator seated before the usual work table D .

As herein shown, the mechanism for actuating and controlling the cutter-carrier is very

simple, strong and compact, and not liable to get out of order.

As the lever arm b rocks with the rotation 70 of the cam, the ball and socket connection with the slide-block a^2 gives a positive yet easy connection with the cutter-carrier a' .

While we have shown a roll d^3 mounted on the pin d^2 to enter the cam groove, it is obvious that any other suitable stud might be used, and while it is preferable to bring the end of the stud d' into positive engagement with the screw 10, to lock the cutter-carrier in inoperative position, it will be obvious that 80 the cutter-carrier could be held inoperative by moving the cam roll or stud d^3 onto the smaller cylindrical portion e^x of the cam, if desired, or against a part of the arm A , with the same results. 85

Our invention is not restricted in its application to the precise form of sewing machine partly illustrated herein, as it is adapted to be used with any class of machine having a conveniently located rotating shaft to which 90 the actuating cam may be secured.

We claim—

1. In a sewing machine, a cutter, a reciprocating cutter-carrier, a rocking lever connected thereto to reciprocate it, a rotating 95 cam, connections intermediate said cam and lever, to rock the latter, and means to move said connections independent of the lever into and out of operative contact with the cam, to thereby actuate or stop the cutter-carrier during the operation of the machine, substantially as described.

2. In a sewing machine, a cutter, a reciprocating cutter-carrier, a rocking lever connected thereto to reciprocate it, a rotating 105 cam, an arm laterally movable with relation to and connected to rock said lever, a stud on said arm to operatively contact with said cam, and means to move said arm laterally to disengage it from the cam, to thereby stop the 110 reciprocation of the cutter-carrier during the operation of the machine, substantially as described.

3. In a sewing machine, a cutter, a reciprocating cutter-carrier, a rotating cam, a rocking 115 sleeve, a lever connected rigidly thereto to reciprocate said cutter-carrier, a spring-controlled shaft longitudinally movable and rotatable in the sleeve, and an arm on said shaft connected to the rocking lever and having a 120 stud adapted to operatively contact with said cam, whereby a longitudinal and rotative movement may be given the shaft by the operator so as to disengage said stud and cam and lift the cutter-bar, substantially as described. 125

4. In a sewing machine, a cutter, a reciprocating cutter-carrier, a rocking lever connected thereto to reciprocate it, a rotating 130 cam, connections intermediate said cam and lever, to rock the latter, means to move said connections into and out of operative contact with the cam, to thereby actuate or stop the cutter-carrier during the operation of the ma-

chine, and a locking device to positively hold the cutter-carrier in inoperative position, substantially as described.

5. In a sewing machine, a cutter, a reciprocating cutter-carrier, a rocking lever connected thereto to reciprocate it, a rotating cam, an arm laterally movable with relation to and connected to rock said lever, a stud on said arm to operatively connect with said cam, and means to move said arm laterally and to rotate it in one direction to thereby withdraw the stud from the cam to stop the reciprocation of the cutter-carrier during the operation of the machine, and a barrier wall 15 on said cam to limit the rotative movement of the arm and stud in the opposite direction and serve as a guide for the entrance of the stud into the channel of the cam, substantially as described.

6. In a sewing machine, a cutter, a reciprocating cutter-carrier, a rocking lever connected thereto to reciprocate it, a rotating cam, connections intermediate said cam and lever, to rock the latter, and means located in line with the fulcrum of the said lever, to 25 move said connections into and out of operative contact with the cam, to thereby actuate or stop the cutter-carrier during the operation of the machine, substantially as described. 30

In testimony whereof we have signed our names to this specification in the presence of two subscribing witnesses.
